UNITED STATES PATENT OFFICE

137,452

DESIGN FOR A BLOUSE

Joe Koret, San Francisco, Calif.

Application January 3, 1944, Serial No. 112,155

Term of patent 7 years

To all whom it may concern:

Be it known that I, Joe Koret, a citizen of the United States and a resident of the city and county of San Francisco, State of California, have invented a new, original, and ornamental Design for a Blouse, of which the following is a specification, reference being had to the accompanying drawing, forming a part thereof.

Fig. 1 is a front view of a blouse as seen slightly in perspective and showing my new design.

Fig. 2 is a rear view of the blouse of Fig. 1 shown in somewhat reduced scale.

I claim:

The ornamental design for a blouse, substantially as shown and described.

JOE KORET.
